UNITED STATES PATENT OFFICE.

CHARLES H. ALLEN, OF PENN YAN, NEW YORK, ASSIGNOR TO YATES LUMBER COMPANY, OF PENN YAN, NEW YORK, A CORPORATION OF NEW YORK.

MECHANISM FOR ATTACHING WIRE HANDLES TO BASKETS.

Application filed January 14, 1927. Serial No. 161,103.

My invention relates to a mechanism for attaching wire handles to baskets, with more particular reference to the type of handle that is affixed to the conventional form of grape basket.

A principal object of the invention is to afford a simple mechanism, of comparatively few parts, and which can be operated in an accurate and reliable fashion.

Another purpose of the improvement is to provide means that will enable an operator to rapidly apply handles to baskets, in such a way as to insure their being properly positioned and rigidly secured.

To these and other ends, the invention consists in the construction and combination of parts that will appear clearly from the following description when read in conjunction with the accompanying drawings, the novel features being pointed out in the claims following the specification.

In the drawings:

Figure 1 is a side elevation of a machine including a preferred embodiment of the invention;

Figure 2 is a front view of the same;

Figure 3 is a plan view showing a basket and handle in position, preparatory to securing the handle to the basket;

Figure 4 is a similar view showing the same parts after the jaws have been operated to move the attaching devices into engagement with the basket;

Figure 5 is an enlarged plan view, similar to Figure 4, but illustrating in horizontal section the parts in the plane of the attaching devices;

Figure 6 is a detailed sectional view on the line 6—6 of Figure 5;

Figure 7 is a side elevation of a basket, partially broken away, showing affixed thereto a handle of the type for which the present mechanism is designed;

Figure 8 is an edge elevation of a wire handle, partially broken away, and showing the position of the attaching device or prong before it is secured to the basket, and

Figure 9 is a side view of the same.

The invention is susceptible of different possible applications, and herein shown as designed for affixing to grape baskets and the like a wire handle of the general type illustrated in Figures 7 to 9 inclusive, and including a loop portion 1 that is engageable on the inside of the basket and an attaching de-

vice or prong 2 that is engageable on the outside of the basket and is forced inwardly until it pierces the basket and occupies a position between the two sides of the loop 1. The wire handle shown forms no part of my invention, but is of old form and is illustrated here to show the application of the mechanism of this invention as designed to accommodate a handle of this character.

In addition to the portions 1 and 2 just referred to, the handle further includes shoulders 3, sides 4 and a top portion 5, as illustrated in Figures 3 to 5 inclusive. The mechanism disclosed includes a table or handle supporting means 6 that is provided with positioning members 7 preferably in the form of stops of the shape illustrated and fixed at the front edge of the table 6 to engage exteriorly of the sides 4 of the handle, and retain the latter in proper relationship to the basket. The table or handle support 6 is mounted upon or forms part of a base 8 which may be suitably arranged on a supporting structure 9 by means of lugs or brackets 10, or the base 8 may be otherwise mounted to suit the convenience of the operator.

11 designates a basket support, preferably curved as shown to conform to the inside of one end of the basket and hold it in position as shown in Figure 1. The basket support 11 is mounted upon brackets 12 suitably attached to the base 8.

The positioning stops 7 are located adjacent to the forward edge of the table 6 and arranged in front of said forward edge, and adjacent thereto is a handle engaging member or block 13 mounted on a pin 14 and held in place by screws 15. The block 13 is loosely arranged on the pin 14 and screws 15 so as to permit of slight play both vertically and horizontally to enable accurate centering with relation to the handle and basket. The sides of the block 13 are inclined vertically and provided with metal wear plates 16 against which the prongs 2 of the wire handle engage as they are forced inwardly through the basket. The block 13 occupies a position inwardly of the handle and opposite to the attaching devices and also inside the basket 17, which is located on the aforesaid support 11 with its side walls located between the ends of the block 13 and the movable jaws that will be described presently. 18 are positioning guides which serve to properly locate the basket as it is inserted on

the support 11, inward movement of the top of the basket being limited by its engagement with the front edge of the table 6.

19 designate the jaws which serve to move 5 the attaching devices into engagement with the basket, said jaws being provided with convex operative faces having grooves 20 therein to cooperate with the portion 2 of the wire handle. Each jaw 19 is pivoted at 21 10 and includes a rearwardly extending portion 22 while 23 are links pivotally connecting the extensions 22 of the jaws to a reciprocating slide 24, the latter being movable in a slot 25 in the table. 26 is an operating lever having 15 a handle 27 and connected to the slide 24 by a slot 28 and pin 29, so that by moving the lever first in one direction and then in the other, the jaws 19 are caused to simultaneously move from the position shown in Figure 3 to that 20 shown in Figure 4 and back again.

In the operation of the machine, the mechanism is initially in the position shown in Figure 3 when the operator inserts a handle, and thereupon a basket, positioning both as 25 shown in said Figure 3. Thereupon handle 27 and lever 26 are moved to the position shown in Figure 4, causing the jaws to engage the attaching prongs 2 and move them inwardly through the side walls of the basket 30 and against the block 13, as shown in Figure 5, thereby firmly affixing the handle to the basket. The lever 26 is then returned to the initial position shown in Figure 3 and the basket removed with the handle affixed thereto. The parts are now ready for a repetition 35 of the operation just described.

While the invention has been disclosed with reference more or less to a particular structure, it is not limited to the details or 40 arrangements or particular sequence of operations herein disclosed, and this application is intended to cover any modifications or departures coming within the intent of the improvement or the scope of the following 45 claims.

I claim:

1. A machine for attaching a wire handle to a basket comprising a handle engaging block loosely mounted for slight movement 50 relatively to the handle and positionable interiorly of the handle with opposite portions of the block engaging opposite portions of the handle, jaws movable toward the handle engaging member to force the handle attaching devices through the basket, and means for effecting simultaneous movement of the jaws.

2. A machine for attaching a wire handle to a basket comprising a handle supporting

table, positioning devices on the table engageable exteriorly of a handle, a block loosely mounted at the front of the table and positionable interiorly of the handle at points opposite to the handle attaching devices, laterally movable jaws operable toward and from the block, and means for effecting simultaneous movement of the jaws.

3. A machine for attaching a wire handle to a basket comprising a basket support, a handle supporting table, positioning stops on the table for engaging a handle exteriorly at 70 opposite points, a block loosely mounted at the front of the table for engaging the handle interiorly at points opposite to its attaching devices, and oppositely movable jaws engageable with the attaching devices to move them 75 toward said block.

4. A machine for attaching a wire handle to a basket comprising a basket support, a handle supporting table, positioning stops on the table for engaging a handle exteriorly 80 at opposite points, a loosely mounted block at the front of the table for engaging the handle interiorly at points opposite to its attaching devices, laterally movable jaws engageable with the attaching devices to move them 85 toward said block, and means for effecting simultaneous movement of the jaws.

5. A machine for attaching a wire handle to a basket comprising a flat handle supporting means having positioning stops thereon extending inwardly from its front edge, a 90 loosely mounted handle engaging block located adjacent to the front edge of said supporting means for engagement interiorly of the handle at points opposite to its attaching devices, and jaws simultaneously movable to effect entrance of the handle attaching devices through the walls of a basket and against said block.

6. A machine for attaching a wire handle 100 to a basket comprising a flat handle supporting means having positioning stops thereon extending inwardly from its front edge, a handle engaging block located adjacent to the front edge of said supporting means for engagement interiorly of the handle at points 105 opposite to its attaching devices, and jaws simultaneously movable to effect entrance of the handle attaching devices through the walls of a basket and against said block, said 110 block being loosely mounted to permit centering with reference to the handle and movable jaws.

In witness whereof, I have hereunto signed my name.

CHARLES H. ALLEN.
